UNITED STATES PATENT OFFICE.

SAMUEL JAMES EVERETT, OF THORNTON HEATH, ENGLAND.

HYPODERMIC SYRINGE AND NEEDLE THEREFOR.

Application filed April 19, 1926, Serial No. 102,991, and in Great Britain April 30, 1925.

This invention comprises improvements in and connected with hypodermic syringes and needles therefor. Heretofore, when a hypodermic needle has been fixed in the nipple 5 or nozzle constituting the mount for the needle on the syringe, the said needle has been inserted into a small bore formed in the mount and has been fixed therein, generally by soldering. One object of these improvements is to provide a more effective and economical method for fixing the needles in the mounts.

Needle head devices machined to have various external formations, have been attached to hypodermic needles by burnishing, swaging and like operation, and the mouth of the bore in such heads has been countersunk. The needle head of these improvements, however, is distinguished from 20 these known heads by the fact that it is forced through a die for attaching it to the needle and for adapting it for fixing in the needle mounting.

According to this invention, the needle is 25 inserted into the bore of a small cylindrical stamping or piece of tubing adapted to form the head and the latter, with the inserted needle, is forced into and through a die which reduces the diameter of the cylindrical piece, 30 and extends its length. The needle mount is formed with a tapered socket or hole, a slight taper being sufficient for the cylindrical head to fit into and the needle is fixed in the mount by forcing the cylindrical head 35 tightly into the tapered hole or socket. Solder may be used for making the joint more secure but in the ordinary way the security of the mounting attained by the tight engagement of the tapered parts is all sufficient for the purpose.

In order to enable the invention to be readily understood, reference is made to the accompanying drawing illustrating examples of suitable constructions on an enlarged scale 45 in which drawing:—

Figure 1 is a central longitudinal section of a hypodermic needle having its blunt end inserted into a tubular head and showing in elevation the plunger by which the head is 50 forced through a die.

Figure 2 is a section of the die through which the head is forced.

Figure 3 is a section corresponding to Figure 1 showing the needle with the tubular head fixed thereto after having been forced 55 through the die.

Referring to Figure 1, *a* is a tubular hypodermic syringe needle having its blunt end inserted into a cylindrical tubular blank or head *b* and *c* is a plunger for forcing the 60 said head through a die *d* shown in Figure 2. This die is formed with a tapered hole or cavity *e* extending therethrough. The head *b* having the blunt end of the needle *a* inserted into it as shown in Figure 1, is introduced into the mouth of the hole or cavity of the die *d* and by application of pressure by the plunger *c*, the head is elongated and compressed around the needle *a* so as to be very tightly engaged with the 70 latter. Indeed, a fluid-tight joint is produced between the needle and the head *b*. Moreover, owing to the shape of the pointed end of the plunger *c* a conical recess is imparted to the outer end of the head *b* as 75 will be readily understood from Figure 3. Thus, the head *b* is now tightly fitted to the blunt end of the needle but slightly elongated and is ready for insertion into a syringe 80 nozzle.

I claim:—

1. In the production of hypodermic needles, the method of forming heads thereon, which comprises inserting the blunt end of the needle into a tubular, cylindrical metal 85 blank, and forcing the blank with the needle therein through a reducing die, thereby elongating the blank and simultaneously effecting a permanent connection of the needle and blank.

2. In the production of hypodermic needles, the method of forming heads thereon which comprises, surrounding the blunt end of the needle with a tubular cylindrical metal blank, and forcing the assembled needle and 95 blank through a reducing die, whereby the blank is elongated while being pressed permanently onto the needle.

3. In the production of hypodermic syringe needles, the method of forming heads 100 thereon, which comprises arranging a tubular cylindrical metal blank on the blunt end of the needle, and forcing the assembled needle and blank through a reducing die by means of a conical plunger engaging the end 105 of the blank, thereby forming a conical cavity in the end of the head blank and simultaneously elongating the latter while forming a permanent connection between the needle and blank.

SAMUEL JAMES EVERETT.
